(57) **CLAIM**

The ornamental design for a docking station, as shown, and described.

DESCRIPTION

FIG. 1 is a perspective view of the docking station;
FIG. 2 is a right side view of the docking station;
FIG. 3 is a left side view of the docking station;
FIG. 4 is a front view of the docking station;
FIG. 5 is a rear view of the docking station;
FIG. 6 is a top view of the docking station;
FIG. 7 is a bottom view of the docking station;
FIG. 8 is an alternate embodiment of the right side of the docking station; and,
FIG. 9 is an alternate embodiment of the rear of the docking station.
Broken lines shown in the drawings illustrate portions of the docking station, and form no part of the claimed design.
